UNITED STATES PATENT OFFICE.

GUSTAV KRAFFT, OF SCHWELM, GERMANY.

APPARATUS FOR MAKING SOAP-BUBBLES.

SPECIFICATION forming part of Letters Patent No. 655,248, dated August 7, 1900.

Application filed January 17, 1900. Serial No. 1,762. (No model.)

To all whom it may concern:

Be it known that I, GUSTAV KRAFFT, a subject of the Emperor of Germany, residing at Ostenstrasse 11, Schwelm, in the Province of 5 Westphalia, Germany, have invented a new and useful Apparatus for Making Soap-Bubbles, of which the following is a full, clear, and exact specification.

My invention has for its object a toy for 10 children consisting of a simple apparatus for inflating soap-bubbles from soap-water which is constantly contained in the apparatus and kept therein for use, so that the apparatus may at any time allow the producing of bubbles, the filling being for a long time of use. 15

On the accompanying drawings, Figure 1 is a cross-section of the apparatus; Fig. 2, a plan thereof, partly in section.

The apparatus consists of a hollow tubular or otherwise shaped piece *a*, tending as 20 a receptacle for receiving the soap-water, which is filled therein through the neck *b*. Said piece has more or less the shape of a bottle. It is provided with a foot *c* or base 25 *e*, formed like a ball, to contain enough soap-water. It may, however, have any other conveniently-shaped form of base, so, for instance, as shown by the dotted line *d*, Fig. 1. The neck of the bottle is closed by a stopper 30 *e*, of any suitable material, to prevent the water from escaping when the apparatus is held in the slanted position. The walls of the bottle are broken through, so as to allow

a pipe *f* to be stuck through the bottle, the diameter of which is smaller than that of the 35 bottle, so that free spaces *g* are left around the tube to allow the water to circulate. The lower part of the pipe *f*, extending from the bottle, is made conically, and in it is inserted a second conical pipe *g*, forming one part 40 with pipe *f* and forming also a channel *h* in said pipe. This channel has connection with the bottle by a small opening *i*, cut in the wall of pipe *f*. When blown in the pipe *f*, there is produced in the channel *h* a sucking 45 stream of air, by which the soap-water is caused to enter the channel *h*, where it is driven to the orifice of the pipe in a fine spray and inflated at the end thereof to a bubble, as seen in Fig. 1.

What I claim, and desire to secure by Letters Patent, is—

As an article of manufacture, an apparatus for producing soap-bubbles consisting of a bottle *a* of any shape and size which is 55 closed by a stopper and filled with soap-water said bottle being crossed by a pipe *f* its downward-extending piece being pointed and having inserted therein a second pipe to form a channel within pipe *f* which has connection 60 with the bottle for the purpose described and set forth.

GUSTAV KRAFFT.
